UNITED STATES PATENT OFFICE.

HORACE N. PACKARD, OF WAUWATOSA, WISCONSIN, ASSIGNOR TO THE CUTLER-HAMMER MFG. CO., OF MILWAUKEE, WISCONSIN, A CORPORATION OF WISCONSIN.

METHOD OF AND MEANS FOR DETERMINING THE HEATING VALUE OF COMBUSTIBLE GASES.

Application filed December 24, 1919, Serial No. 347,227. Renewed February 12, 1926.

This invention relates to a method of and means for determining the heating value of combustible gases.

While there has been a great demand for a

5 practical calorimeter for this purpose and while various forms of such calorimeters have been heretofore proposed it is still the general practice to determine the heating value of combustible gases by laboratory 10 tests and calculations, the calorimeters heretofore proposed being open to various objections, including inaccuracy, unreliability of operation and inability to function continuously.

15 The present invention has among its objects to provide a method whereby the total heating value of gases, as defined by the U. S. Bureau of Standards, which value includes the latent heat of vaporization of the 20 water of combustion, may be readily determined with accuracy.

Another object is to provide a reliable calorimeter for carrying out such method, such calorimeter to function continuously 25 and to record as well as determine the heating value of the test gas.

Another object is to provide a calorimeter of the aforesaid character wherein the heat given off by combustion of the test 30 gas is transferred to a stream of fluid and the temperature rise of such fluid utilized in determining the heating value of the test gas.

Various other objects and advantages of 35 the invention will hereinafter appear.

The accompanying drawing diagrammatically illustrates one form of calorimeter for carrying out the aforesaid method and the 40 same will now be described, it being understood that the calorimeter illustrated may be modified in various ways without departing from the scope of the appended claims.

Referring to the drawing, a burner 1 is 45 provided for the test gas, said burner being enclosed within a tube 2 closed at its upper end whereby the products of combustion are forced to leave said tube through its lower end. The tube 2 is surrounded by a tube 3 through which a stream of air is passed to 50 absorb the heat given off by the burner through the tube 2. The stream of air passes upwardly through the tube 3 which is open

at its upper end but provided with a cap 4 whereby the stream of air after leaving the same is forced to traverse a reflexed path for 55 a purpose hereinafter set forth.

The products of combustion are thus prevented from mixing with the stream of cooling air and if the gas supplied to the burner is maintained at the temperature of the exit 60 products of combustion the water of combustion will be completely condensed from the products of combustion with the result that the latent heat of vaporization of such water will be transferred to the stream of 65 cooling air. Thus if the rate of flow of the cooling air and its temperature rise are accurately determined the total heating value of the test gas can be readily determined and if the rate of flow of the test gas and the 70 cooling air are maintained proportional the temperature rise of the cooling air will be directly proportional to the heating value of 75 the gas.

The cooling air and test gas inclusive of 80 a supply of air for purposes of combustion, are supplied in quantities bearing a constant ratio by three wet displacement meters 6, 7 and 8 which may be of standard form. However accurate quantitative proportionality of the test gas and combustion air is not necessary provided the air be supplied in moderate excess or at least in quantity sufficient to insure complete combustion under all conditions. The meter 6 supplies air 85 to the tube 3 while the meters 7 and 8 respectively supply gas and air to a mixing chamber 9 associated with the burner and said meters are coupled together by any suitable means represented by sprocket chains 10 and 90 11 for operation at given relative speeds. Further, all of said meters are mounted in a closed tank 12 containing a quantity of 95 water in which they are partially immersed to maintain them at like temperatures, although said meters have water levels independent of the tank water whereby the water level of each may be adjusted as in any standard wet meter for proper registration. The air meters are so arranged that their inlets take air directly from the tank which is supplied with air by a blower 14 driven by a motor 15. The blower supplies air to 100 the tank through a compartment 16 which

is designed to force the incoming air into direct contact with the water to saturate the air and to bring its temperature to that of the water. The gas meter is connected 5 to a supply line 17 through a regulator 18 of standard form which functions to maintain a pressure on the inlet side of said meter equivalent to the air pressure within the tank, the gas being saturated in passing to 10 the meter.

Thus provision is made for supplying air and gas to the meters under like temperature, pressure and saturation conditions and for maintaining a fixed speed ratio of the 15 meters and hence assuming proper adjustment of the three streams of fluid the temperature rise of the stream of air to which the heat of combustion is transferred will always be directly proportional to the heating 20 value of the gas regardless of its rate of flow. For example, assuming that for a given sample of gas the air to which the heat of combustion is transferred shows a temperature rise of 10° such temperature 25 rise will obtain even though the rate of flow of the gas is doubled, for the rate of flow of the air will also be doubled. On the other hand, assuming the heating value of the sample of gas to be reduced to one-half of that 30 formerly assumed, the temperature rise of the air will be reduced to 5° .

Resistance thermometers 20 and 21 of the armored type are provided in the tube 3 to measure the temperature rise of the air 35 to which the heat of combustion is transferred, the thermometer 20 being arranged adjacent to the inlet end of said tube and the thermometer 21 adjacent to the outlet end thereof. These resistance thermometers are 40 utilized in a Wheatstone bridge for controlling the marker of a clock-driven B. t. u. recorder 22. The bridge is utilized to control a galvanometer 23 having associated with its needle 24 a switch 25 to control 45 the operating magnets 26 and 27 of a ratcheting mechanism 28 which serves to both operate the marker of the recorder and a rheostat 29. The resistance thermometers are respectively connected to opposite terminals 50 of the galvanometer and to one side of a D. C. supply circuit $L-L'$, through the rheostat 29, while resistances 31 and 32 are respectively connected to opposite terminals 55 of the galvanometer and to the opposite side of said D. C. circuit to complete the Wheatstone bridge. The arrangement is such that with the arm of rheostat 29 in one position the resistance of said rheostat 60 is divided equally between the circuits of the two resistance thermometers whereas movement of said arm from such position increases the resistance included in one thermometer circuit and correspondingly decreases the resistance included in the other 65 thermometer circuit. Also the arrangement

is such that for a given movement of the rheostat arm the marker of the recorder is moved a given distance transversely of the chart of said recorder.

The switch 25 comprises two series of 70 contacts 36 and 37 the contacts of one series to be successively engaged by the galvanometer needle when deflected in one direction and those of the other series to be successively engaged thereby when deflected in the 75 opposite direction. Further, the switch comprises two segments 38 and 39 carried by a reciprocable cross head 40 and operable to clamp the galvanometer needle between the segment 38 and any one of the 80 contacts 36 or between segment 39 and any one of contacts 37. The contacts 36 and 37 are supplied with current from a supply circuit L^2, L^3 , which may be either A. C. or D. C. through a contact drum 41 operated by the blower motor 15. The contact segments 38 and 39, on the other hand, are respectively connected to the windings of magnets 26 and 27 which have a common return to one side of the supply circuit L^2-L^3 90 whereby operation of the switch 25 provides for energization of said switches selectively when the galvanometer needle is deflected from zero position. The segments 38 and 39 of the switch are operable by a solenoid 42 which is also controlled by the drum 41. 95

The drum 41 is provided with a segment 43 having one or more sets of spaced extensions 44, 45 and 46 of different lengths, said segments being provided to co-operate with 100 contact brushes 47 to 51 inclusive. The segment 43 is designed to bridge brushes 47 and 48 to complete the circuit of solenoid 42 but only during a part of each revolution of the drum whereby continuous rotation 105 of the drum will periodically energize and de-energize said solenoid for intermittent operation of the switch 25. All of the segment extensions are designed to co-operate with brush 49 to complete circuit to the outermost contacts 36 and 37 of switch 25 while extensions 45 and 46 are designed to 110 co-operate with brush 50 to complete circuit to the intermediate contacts 36 and 37, extension 46 alone co-operating with brush 51 115 to complete circuit to the adjacent contacts 36 and 37. Thus assuming the segment to be provided with a single set of extensions and assuming the galvanometer needle to be deflected, a single revolution of the drum 120 will provide for operation of switch 25 and for energization and de-energization of one of the magnets of the ratcheting mechanism either one, two or three times according to the degree of deflection of such needle. When the needle is only slightly deflected one revolution of the drum will cause only one step of operation of the ratcheting mechanism but when the needle is deflected 125 to a greater degree one revolution of the 130

drum will cause a proportionally greater number of operations of said mechanism.

Thus assuming the Wheatstone bridge to be balanced and the marker of the recorder properly positioned for the instant heating value of the test gas any variation in the heating value of the gas and consequent variation in temperature rise of the cooling air will unbalance the Wheatstone bridge causing the galvanometer needle to be deflected in one direction or the other. Thereupon the switch 25 will function to intermittently energize the appropriate magnet of the ratcheting mechanism thereby shifting the marker of the recorder to indicate the variation in the heating value of the test gas, it being remembered that the temperature rise of the cooling air varies in direct proportion to the change in heating value of the test gas. Also the ratcheting mechanism in so operating functions to operate the rheostat in a step by step manner until the Wheatstone bridge is again balanced thereby arresting the operation of the ratcheting mechanism. Thus the apparatus provides for making a continuous record of the heating value of the test gas.

Moreover the apparatus in measuring the temperature rise of the air compensates for the variables which must be taken into consideration in determining the heating value of the test gas. Heat losses due to incomplete transfer of heat from the burning gas to the cooling air are compensated by passing the stream of cooling air through the reflexed path above described to preheat the incoming air after passing the inlet thermometer. A certain amount of the heat transferred to the air is thus twice measured and the twice measured heat is so regulated that errors due to heat losses are eliminated. On the other hand the resistances of the Wheatstone bridge are so designed as to compensate for variations of specific heat of the saturated air with temperature and also for variations of the heating value of the gas as measured due to its variable dilution with water vapor at different temperatures. Compensation for both variables may be accomplished by designing the resistance thermometers for given changes in the resistance values thereof with given changes in the temperature and in the apparatus shown the resistance thermometers are formed of suitable compositions of metals to afford them the desired characteristics. However, compensation for such variables may be accomplished in other ways as by the provision of a variable resistance temperature difference coil in the Wheatstone bridge. Also, as will be understood, the Wheatstone bridge may be designed to compensate for other variables not encountered in determining the heating value of the test gas by the method herein disclosed.

While in practice it is preferred to employ the above described Wheatstone bridge measuring and recording means because of the accuracy and reliability thereof it is, of course, to be understood that other known temperature measuring and recording means may be employed in lieu thereof. For example, the thermometers 20 and 21 may be of known construction to function as recording thermometers or as elements of a differential recording thermometer.

What I claim as new and desire to secure by Letters Patent is:

1. The method of ascertaining the heating value of a combustible fluid which comprises, effecting combustion of such fluid in the presence of a sufficient quantity of air and determining the effect of combustion upon a stream of air bearing a definite quantity ratio to the combustible fluid and maintained separate from the combustion products.

2. The method of ascertaining the heating value of a combustible fluid which comprises determining the thermic effect upon a stream of fluid whose temperature pressure volume relation obeys the same physical law as the test fluid of combustion of the test fluid in the presence of an assured sufficiency of combustion air and in a relation to transfer the heat of combustion to said second fluid.

3. The method of ascertaining the heating value of a combustible fluid which comprises effecting complete combustion of a quantity of such fluid in air, and effecting a heat transfer between the resultant combustion products and a quantity of a cooling fluid whose temperature pressure volume relation obeys the same physical law as said combustible fluid and definitely proportioned to the quantity of said combustible fluid, and effecting transfer to the cooling fluid of the heat of vaporization of any water produced by such combustion.

4. The method of ascertaining the heating value of a combustible fluid which comprises effecting complete combustion of a quantity of such fluid in air, and effecting a heat transfer between the resultant combustion products and a quantity of a cooling fluid whose temperature pressure volume relation obeys the same physical law as said combustible fluid and definitely proportioned to the quantity of said combustible fluid, and effecting cooling of the combustion products by the cooling fluid to the temperature of the combustible fluid prior to the heat transfer, to thereby prevent loss of heat of vaporization of any of such products which are liquid at such temperature.

5. The method of ascertaining the heating value of a combustible fluid which comprises, effecting combustion of a complete combustion mixture of such fluid and air, and effecting a heat exchange between the

- resultant combustion products and a definitely proportioned quantity of cooling fluid, whose temperature pressure volume relation obeys the same physical law as said 5 combustible fluid, under conditions, including counter flow of said fluids, such as to effect cooling of the combustion products by the cooling fluid to the temperature of the combustible fluid prior to the heat transfer, 10 to thereby prevent loss of latent heat of vaporization of any of such products which are liquid at such temperature.
6. The method of determining the heating value of a stream of combustible fluid 15 by determining the total heating effect of the combustion thereof upon another stream of fluid, which comprises subjecting both fluids to like temperature, pressure and saturation conditions, supplying said fluids in 20 streams bearing a definite volumetric ratio to one another and maintaining the streams of said fluids separate during the heat transfer.
7. The method of ascertaining the heating 25 value of a combustible gas by determining the effect of the heat of combustion thereof upon a cooling fluid, which comprises subjecting the gas and cooling fluid to like saturation conditions, supplying the 30 same in quantities having a definite ratio and eliminating the effect of variations in the heating value of the gas as measured due to its variable dilution with water vapor at different temperatures.
8. The method of ascertaining the heating 35 value of a combustible gas by determining the effect of the heat of combustion thereof on a cooling fluid, which comprises subjecting the gas and cooling fluid to like 40 saturation conditions, supplying the same in quantities having a definite ratio and eliminating the effect of variations of specific heat of the saturated air with temperature.
9. The method of determining the heating 45 value of a combustible fluid which comprises subjecting to the heat of combustion thereof a cooling fluid supplied in a definite quantitative proportion thereto, augmenting 50 the apparent value of the temperature rise of the cooling fluid by causing a supplemental transfer of heat thereto to thereby compensate for heat losses incident to the first mentioned heat transfer, and measuring the 55 total resultant temperature rise of the cooling fluid.
10. The method of determining the heating 60 value of a combustible fluid which comprises subjecting a cooling fluid to the heat of combustion of the former fluid, such heat of combustion including the latent heat of vaporization of the water of combustion, proportioning the supplies of cooling fluid and combustion fluid for a definite quantity 65 ratio thereof and measuring the tempera- ture rise of the cooling fluid caused by the heat of combustion.
11. The method of determining the heating 70 value of a stream of combustible gas by measuring the temperature rise of a stream of cooling fluid subjected to the heat of combustion of such gas, which comprises supplying such gas and fluid under like temperature, pressure and saturation conditions, maintaining a definite volumetric ratio of 75 the supplies of such fluids, augmenting the apparent resultant temperature rise of the fluid by causing a supplemental transfer of heat thereto to thereby compensate for heat losses and eliminating the effect of variations of the heating value of the gas as supplied due to its variable dilution with water vapor at different temperatures. 80
12. The method of determining the heating 85 value of combustible gases which comprises supplying under like temperature, pressure and saturation conditions test gas, air to be mixed therewith and a cooling fluid, maintaining definite volumetric proportionality of said gas and fluid, burning the mixture of gas and air and subjecting the cooling fluid to the resulting heat of combustion, and measuring the temperature rise of the cooling fluid resulting from the heat of combustion. 90
13. A calorimeter for determining the heating 95 value of combustible gases by measuring the temperature rise of a fluid subjected to the heat of combustion of the test gas and air, which includes means for subjecting the gas, air and fluid to like temperature, pressure and saturation conditions and associated means for supplying said gas and fluid in continuous streams having a definite volumetric ratio. 100
14. Apparatus for determining the heating 105 value of combustible gases including a plurality of wet displacement meters to respectively supply the test gas, combustion air and a cooling fluid, and means insuring substantial equalization of the temperatures of said meters. 110
15. Apparatus for determining the heating 115 value of combustible gases including a plurality of wet displacement meters to respectively supply the test gas and a cooling fluid and means insuring substantial equalization of the pressures of the gas and cooling fluid supplied to said meters. 120
16. Apparatus for determining the heating 125 value of combustible gases including a plurality of wet displacement meters to respectively supply the test gas and a cooling fluid, said meters being connected to insure a constant speed ratio thereof and means whereby the gas and cooling fluid are subjected to like temperature and pressure conditions. 125
17. Apparatus for determining the heating 130 value of combustible gases including a

plurality of wet displacement meters to respectively supply the test gas and a cooling fluid, and a tank containing a quantity of fluid in which all of said meters are partially immersed to maintain like temperatures thereof.

18. Apparatus for determining the heating value of combustible gases including a plurality of wet displacement meters to respectively supply the test gas and air, a closed tank in which said meters are mounted, said tank being supplied with air under pressure for said air meter and a regulator within said tank to regulate the pressure of the gas supplied to said gas meter according to the air pressure within said tank.

19. Apparatus for determining the heating value of combustible gases including a closed tank containing a fluid, a plurality of wet displacement meters mounted therein to be maintained at like temperatures by such fluid, means for supplying said tank with air for certain of said meters and means for supplying gas to another of said meters and regulating the pressure thereof to substantially equal the air pressure within said tank.

20. Apparatus for determining the heating value of combustible gases comprising a burner, means for supplying under like temperature, pressure and saturation conditions gas to be supplied to said burner and air to be supplied in proximity to said burner, said means supplying streams of gas and air whose volumes are in definite ratio and means for measuring the temperature rise of the air subjected to the heat given off by the burning gas including means compensating for variations of the heating value of the gas as measured due to its variable dilution with water vapor at different temperatures.

21. Apparatus for determining the heating value of combustible gases comprising a burner, means for supplying under like temperature, pressure and saturation conditions gas to be supplied to said burner and air to be supplied in proximity to said burner, said means supplying streams of gas and air whose volumes are in definite ratio, means for measuring the temperature rise of the air subjected to the heat given off by the burning gas including means compensating for variations of specific heat of the saturated air with temperature.

22. Apparatus for determining the heating value of combustible gases comprising a burner, means for supplying under like temperature, pressure and saturation conditions gas to be supplied to said burner and air to be supplied in proximity to said burner, said means supplying streams of gas and air whose volumes are in definite ratio, means for measuring the temperature rise of the air subjected to the heat given off by

the burning gas and means compensating for incomplete transfer of the heat of combustion to the air.

23. Apparatus for determining the heating value of combustible gases comprising a burner, means for supplying under like temperature, pressure and saturation conditions gas to be supplied to said burner and air to be supplied in proximity to said burner, said means supplying streams of gas and air whose volumes are in definite ratio, means for measuring the temperature rise of the air subjected to the heat of combustion including means compensating for variation of the heating value of the gas as measured due to its variable dilution with water vapor at different temperatures, and means compensating for incomplete transfer of the heat of combustion to the air.

24. In apparatus for determining the heating value of combustible gases, the combination with a burner of means to supply combustion gas thereto and also to supply a stream of fluid in heat exchanging relation to the products of combustion of the gas, means for effecting counter flow of said fluid after such heat exchange to compensate for incomplete transfer of the combustion heat to such fluid, and means for measuring the temperature rise of said fluid.

25. In apparatus for determining the heating value of combustible gases, the combination with a burner, of means to supply combustion gas thereto and also to supply a stream of fluid in heat exchanging relation to the products of combustion of the gas, means for measuring the consequent temperature of said fluid, and means for transferring heat between the stream of fluid after passing said measuring means and the same stream prior to passing said measuring means to thereby compensate for incomplete transfer of heat to said fluid during the earlier heat exchange.

26. Apparatus for determining the heating value of combustible gases comprising a burner, means for supplying a stream of gas to the burner and a stream of air in proximity to the burner and for maintaining the stream of said air separate from the products of the gas combustion, said means supplying gas and air in quantities having a definite ratio and resistance thermometers in the path of said stream of air, whereby the temperature rise thereof due to the heat given off by the burning gas may be measured.

27. Apparatus for determining the heating value of combustible gases comprising a burner, means for supplying a stream of gas to the burner and a stream of air in proximity to the burner but separated from the products of combustion, said means insuring a definite quantity ratio of the gas and air supplied thereby, a Wheatstone

bridge including resistance thermometers in the path of the stream of air to measure the temperature rise of the air caused by the heat given off by the burning gas and means controlled by said Wheatstone bridge for indicating the heating value of the test gas.

28. Apparatus for determining the heating value of combustible gases comprising a burner, means for supplying a stream of gas to the burner and a stream of air in proximity to the burner, said means insuring a definite quantity ratio of the gas and air supplied thereby, a Wheatstone bridge including resistance thermometers in the path of the stream of air to measure the temperature rise of the air caused by the heat given off by the burning gas and means controlled by said Wheatstone bridge for indicating and recording the heating value of the test gas.

29. Apparatus for determining the heating value of combustible gases comprising a burner for the test gas, means for supplying a stream of cooling fluid in proximity to the burner and means for measuring the temperature rise of the cooling fluid caused by the heat of the burning gas, said measuring means including electrical resistance influenced by changes in temperature to compensate for a variable factor tending to render the temperature rise of the cooling fluid disproportional to the heating value of the test gas.

30. Apparatus for determining the heating value of combustible gases comprising a burner for the test gas, means for supplying a stream of cooling fluid in proximity to said burner and means for measuring the temperature rise of the cooling fluid caused by the heat of the burning gas, said measuring means including a Wheatstone bridge having resistance therein influenced by changes in temperature to compensate for a variable factor tending to render the temperature rise of the cooling fluid disproportional to the heating value of the test gas.

31. Apparatus for determining the heating value of combustible gases comprising a burner, means for supplying a cooling fluid in proximity to said burner and a Wheatstone bridge having resistances to measure the temperature rise of the cooling fluid caused by the heat of the burning gas and to compensate for variable factors tending to render the temperature rise of the cooling fluid disproportional to the heating value of the test gas, such factors including variations of the heating value of the gas due to its variable dilution with water vapor at different temperatures.

32. Apparatus for determining the heating value of combustible gases comprising a burner, means for supplying a stream of cooling fluid in proximity to said burner, a Wheatstone bridge including resistance ther-

momters for measuring the temperature rise of the fluid caused by the heat of the burning gas and indicating and recording means controlled by said Wheatstone bridge.

33. Apparatus for determining the heating value of combustible gases comprising a burner, means for supplying a stream of cooling fluid in proximity to said burner; a Wheatstone bridge including resistance thermometers for measuring the temperature rise of the fluid caused by the heat of the burning gas and indicating and recording means controlled by said Wheatstone bridge, all of said elements being co-ordinated to afford continuous indication and recordation of the heating value of the test gas.

34. In a method of ascertaining the heating value of a flowing combustible fluid, through burning of such fluid and absorption by a proportionate flow of cooling fluid of the heat so liberated, the step which comprises effecting a heat exchange between the cooling fluid subsequent to such absorption of heat thereby and the same fluid at a lower temperature.

35. In a method of ascertaining the heating value of a flowing combustible fluid, through burning of such fluid and absorption by a proportionate flow of cooling fluid of the heat so liberated, the step which comprises effecting a heat exchange between the flow of cooling fluid after such heat absorption and the same fluid undergoing such heat absorption.

36. In a method of ascertaining the heating value of a flowing combustible fluid through quantitative proportioning of such fluid and a flow of cooling fluid, burning of such former fluid and absorption by the cooling fluid of the heat so liberated, the step which comprises effecting preheating of the flow of cooling fluid by the same fluid heated by such absorption.

37. In a method of ascertaining the heating value of a combustible fluid through quantitative proportioning of such fluid and a cooling fluid, burning of such former fluid and absorption by the cooling fluid of the heat so liberated, the step which comprises utilizing the cooling fluid after subjection to such heat exchange for jacketing the fluid undergoing such heat exchange and for effecting a direct transfer of heat to the latter.

38. In a method of ascertaining the heating value of a combustible fluid through quantitative proportioning of such fluid and a cooling fluid, burning of such former fluid and absorption by the cooling fluid of the heat so liberated, the step which comprises utilizing the cooling fluid after such heat exchange, for jacketing and preheating the same fluid undergoing such exchange.

39. In apparatus for ascertaining the heating value of a combustible fluid, the combination with means to effect combustion

of said fluid, of means for effecting a flow of fluid to absorb the heat of such combustion and means for causing a return flow of such fluid after such heat exchange for jacketing the fluid undergoing such exchange.

40. In apparatus for ascertaining the heating value of a flowing combustible fluid, the combination with means to effect combustion of said fluid, of means for effecting a proportionate flow of fluid to absorb the heat of such combustion and means for causing a return flow of such heated fluid for increasing the heat at a given point in the first mentioned flow.
- 10 41. In apparatus for ascertaining the heating value of a flowing combustible fluid, the combination with means to effect combustion of said fluid, of means for causing the combustion products to flow in a given direction, means for effecting an opposite proportional flow of cooling fluid in heat exchanging relation to such combustion products, and means for causing said cooling fluid to flow in heat exchanging relation to its own flow during said first mentioned heat exchange to impart additional heat thereto.
- 20 42. In apparatus for ascertaining the heating value of a combustible fluid, the combination with means to effect combustion of said fluid, of means for causing the combustion products to flow oppositely to and in heat exchanging relation to the flow of combustible fluid to said first mentioned means, means for causing a flow of cooling fluid in heat exchanging relation to said combustion products, and means for caus-

ing a reverse flow of said cooling fluid to jacket its own flow to thereby additionally heat said cooling fluid during said second mentioned heat exchange.

40

43. In apparatus for ascertaining the heating value of a combustible fluid, the combination with means to effect combustion of said fluid, of means for causing the combustion products to flow in a given direction and in heat exchanging relation to the combustible fluid prior to combustion thereof, means for causing an opposite flow of cooling fluid in heat exchanging relation to said combustion products, and means for causing a return flow of said cooling fluid to impart heat to its own flow during said last mentioned heat exchange, for substantially equalizing the temperatures of said cooling fluid and said combustion products.

45

50

55

44. In apparatus for ascertaining the heating value of a combustible fluid, the combination with means to effect combustion of said fluid, of means for causing the combustion products to flow in heat exchanging relation to the flow of combustible fluid to said first mentioned means, means for causing a flow of cooling fluid adjacent to said combustion products to effect a further heat exchange, and means for causing a return flow of said cooling fluid for jacketing the fluids undergoing heat exchange and for imparting heat to certain of the same.
